APPARATUS FOR TRIMMING APPENDAGES
FOR POTTERY WARENorman I. Sebell, Brockton, Mass., assignor to
Onondaga Pottery Company, Syracuse, N. Y.,
a corporation of New York

Application April 28, 1948, Serial No. 23,797

11 Claims. (Cl. 25—22)

1

This invention has to do with a method for trimming appendages, such as handles, lugs, etc., preparatory to their application to articles of pottery ware, and apparatus by which the method can be carried out and the appendages automatically trimmed. Appendages for articles of pottery ware are usually formed by being cast in a two-part mould formed with a plurality of concavities for simultaneously casting a number of handles, or other appendages, at a time. These concavities in the mould are connected by a common runner or sprue, the arrangement being such that the liquid clay or material flows into each concavity at the side of the appendage to be attached to the article of ware. Accordingly, the individual handles after casting are broken away from the sprue, the flash or seam of thin clay at the parting line of the two halves of the moulds is removed and then the side of the appendage broken from the sprue is cut, or trimmed, to provide a surface complementary to the surface of the article of ware to which the appendage is applied, the application being effected by dipping the trimmed or cut surface of the appendage in liquid clay and manually pressing the appendage against the article of ware.

Heretofore it has been the practise to trim such appendages with a single cutter blade passed by manual manipulation through the appendage from one side to the other. This method results in chipping or breaking the appendage on the side from which the cutter blade leaves the appendage.

Machines have been suggested for performing this trimming operation as disclosed in Patents 2,361,312 and 2,413,540. Such machines have been either too complicated and costly, or required an additional amount of handwork making such machines impractical for use in manufacture.

This invention has as an object a method by which appendages for pottery ware can be trimmed to shape and size without chipping, breaking, or otherwise damaging the appendage.

This invention has as a further object an apparatus operable to automatically trim the appendages with great accuracy and uniformity, and to deposit the trimmed appendages successively upon an accumulating table, or the like, where they are made available to the operator that applies the trimmed appendages to the articles of ware known in the trade as a handler.

The invention has as a further object apparatus of the type referred to embodying a struc-

2

ture operable to effect the trimming operation with efficiency and particularly, without chipping or otherwise damaging the appendage.

The invention consists in the novel method and features and in the combinations and constructions hereinafter set forth and claimed.

In describing this invention, reference is made to the accompanying drawings in which like characters designate corresponding parts in all the views.

Figure 1 is a top plan view of an apparatus embodying my invention.

Figure 2 is a side elevational view.

Figure 3 is a view taken on line 3—3, Figure 2.

Figure 4 is a view taken on line 4—4, Figure 1.

Figure 5 is an isometric view of one of the appendage carrying fixtures and contiguous portion of the conveyor.

Figure 6 is a view, corresponding to line 6—6, Figure 4, with parts broken away and parts in section.

Figure 7 is an enlarged fragmentary elevational view of the conveyor indexing mechanism shown in the upper center portion of Figure 3.

Figure 8 is a view taken on line 8—8, Figure 4.

Figure 9 is a sectional view of the driving clutch structure.

Figure 10 is a side elevational view of the appendage retaining mechanism positioned at the upper end of its movement.

The apparatus is built in a suitable framework consisting of a rear pair of vertical members 20, and a forward pair 21 extending upwardly from the floor and having secured to their upper ends a top plate 22, a pair of upper rails 23, and a pair of lower rails 24 extend forwardly from the legs 21 and are secured to a pair of vertical supporting members 25. The upper rails 23 extend forwardly and have affixed to their forward ends a shelf 26 supported by braces 27 carried by the legs 25. The shelf 26 is formed with an arcuate recess to receive a turn table support 28 on which the trimmed appendages are placed. The turn table 28 is mounted on a shaft 29 extending upwardly from a housing 30 containing a gear reduction and which is suitably mounted on the lower rails 24, Figure 2.

The appendages 32 are intermittently advanced to a trimming station by a conveyor mechanism including an endless series of appendage or carrying members, or fixtures. A pair of bearing blocks 33 are secured to the under side of the top plate 22 in proximity to the rear edge thereof, and a similar pair 34 are mounted

on the plate adjacent the forward edge thereof. A shaft 35 is journaled in the bearing blocks 33 and carries a sprocket 36. A shaft 37 is journaled in the forward bearings 34 and carries a sprocket 38. A chain 39 is trained over these sprockets and has secured to it at uniform spaced intervals blocks 40. The rear portion of the top plate 22 is recessed as at 41 to permit the blocks 40 to move upwardly about the sprocket 36, and the forward portion of the top plate 22 is recessed from its forward edge inwardly to permit the fixture blocks 40 to move downwardly about the sprocket 38, the recess terminating at 42, see Figure 6. Guide rails 43 are secured in spaced apart relation to the top of the plate 22 and form a track along which the blocks 40 are moved by the upper run of the chain 39. The blocks 40 are formed with depending flanges 45 which cooperate with the rails 43 to accurately guide the blocks during their movement on the rails. The blocks 40 form the base portion of the appendage carrying members.

The blocks 40 are formed on their upper surfaces with a recess extending to the inner side edges of the blocks, and plates 46 are positioned in these recesses and are adjustable both lengthwise and transversely of the conveyor chain. The plates are secured in the recesses by clamp bars 47 and screws 48.

Each plate 46 is formed with a recess in the top surface thereof adjacent the inner edge of the plate. This recess is of such shape and form as to receive the plastic clay appendage. In the drawings, these recesses 50 are of general ear formation to receive cup handles with the inner edge portion of the handle projecting inwardly beyond the inner edge of the plates 46. It will be understood that the plates 46 are properly recessed to receive the appendage to be trimmed, such as handles, lugs, decorating knobs, etc.

The appendages are placed in the plates 46 at station A, Figure 1. The carriers are intermittently advanced to station B where the appendages are trimmed. The carriers are then advanced forwardly and downwardly around the forward sprocket 38, and the trimmed appendages are deposited on the turn table 28, as indicated in Figure 1, the edges 52 having been trimmed to proper shape and contour at the trimming station B.

The appendages 32 are trimmed by a pair of cutters which are normally maintained in spaced apart relation and which are moved together as each appendage is presented at the station B. These cutters consist of blades 54, 55, mounted on like ends of arms 56, 57, respectively. These arms are journaled at their opposite ends on a pivot pin 60 carried in a bracket 61 mounted on the top plate 22. The blades are detachably secured to the free ends of the arms by being clamped thereto as by clamp bars 63 and screws 64 threading into the arms. The outer end edges of the arms 56, 57, are curved or formed to give the blades 54, 55, the desired shape to trim the appendages to the proper contour lengthwise or axially of the appendages. The distance the blades are positioned from the pivot pin 60 determines the transverse arcuate contour of the appendages. Usually these appendages are affixed to circular pieces of pottery ware, with the appendages extending in a vertical plane. Accordingly, the transverse contour of the trimmed edge of the appendage is complementary to the curvature of the circular piece of ware. The lengthwise or axial contour depends upon the

contour of the piece of ware relative to its vertical axis. This, of course, is usually not on a uniform radius unless the piece of ware happens to be of spherical formation. For example, on a tea-cup, the appendage might not be trimmed on a uniform curvature, but might include two or more curvatures. This situation is taken care of by proper formation of the cutting blades 54, 55, which can be conveniently done by properly contouring the ends of the arms 56, 57, to which the thin steel blades are attached, as described.

Heretofore, appendages have been trimmed by the use of a single blade. In my apparatus, I employ the pair of blades 54, 55, and obtain certain advantages thereby. For example, with the single blade the edge of the appendage into which the blade enters is formed with a sharp and proper contour, but the side of the appendage from which the blade leaves is often chipped, or of ragged formation. With my arrangement, the blades enter opposite side edges of the appendage and meet in biting or nipping engagement at approximately the center of the appendage, whereby both of the outer edges are of sharp and proper formation.

The apparatus herein described will function properly without any additional means of holding the appendages in the plates 46. However, entirely perfect trimming of all forms of appendages is accomplished by applying a slight pressure on the appendage during the trimming operation.

In the structure disclosed, a bracket 65 is hinged at one end to the top plate 22, as at 66. The free end of the bracket overlaps the upper blade arm 56, see Figures 3 and 4. A weight 67 is secured to the bracket adjacent the free end thereof, and a yieldable pad 68 of felt, or like material, is secured to the under side of the weight. The arrangement is such that when the cutters are in open position, as shown in Figure 3, the pad 68 is elevated above the path traveled by the appendages. However, when the cutters are moved toward the appendage, the weighted pad engages the appendage, exerting a slight pressure to hold the same in the recess 50 during the trimming operation, see Figure 4.

The machine includes motion transmitting mechanism for intermittently advancing the carriers 40 and operating the trimming cutters in timed relation. A shaft 70 is journaled in bearing brackets 71 also depending from the under side of the top plate 22. This shaft has secured to it a disk 75, the periphery of which is formed with a cam lobe 76. A crank pin 78 is mounted for rotation in the disk and is formed with a head 79 in which a tubular member 80 is clamped, as by screw 81.

The end of the tube is provided with a shoulder 83 for further assurance that the tube will not move in the head member 79 during that portion of the cycle of operation wherein force is transmitted from the shaft 70 to the member 80. The opposite end of the member 80 is provided with a plug 84 apertured to slidably receive a rod 85, the inner end of which is formed with an enlarged head portion 86. A helical compression spring 87 encircles the rod and is interposed between the plug 84 and the head 86, thereby urging the rod inwardly. The outer end of the rod is threaded for attachment to a link 87 pivotally connected by bolt 88 to an arm 89 freely journaled on the forward sprocket shaft 37. The arm 89 carries a spring actuated pawl 90 arranged to successively engage notches 91 formed

on a ratchet wheel 92 which is secured to the shaft 37. Accordingly, upon rotation of the shaft 70 in a counterclockwise direction, Figure 6, the sprocket wheels 36, 38, are intermittently rotated in the same direction and the appendage carriers 40 are intermittently advanced from right to left, Figures 2 and 6, whereby the appendages are advanced from the loading station A to the trimming station B, Figure 1, and the trimmed appendages deposited upon the accumulating table 28.

The apparatus includes means operable to accurately position the appendages at the trimming station B, whereby all of the appendages will be accurately and uniformly trimmed. As previously explained, the fixture plates 46 are adjustable in the individual carrying blocks 40 both lengthwise and transversely of the conveyor chain. As the blocks 40 advance to the trimming station, a stop member is moved into the path of movement of the carriers 40. This member is fixed in the frame relative to the trimming cutters, and the apparatus further includes provision for yieldingly maintaining the carrier against the stop member during the trimming operation. In this manner, each carrier is accurately positioned lengthwise of the conveyor chain during the trimming operation. This stop member consists of an arm 98 pivoted at one end to a bracket 99 depending from the top plate 22. The opposite end of the arm is formed with an upwardly extending portion 100 having a face 101 against which the carriers abut. The arm 98 is urged downwardly by a compression spring 102 interposed between the arm and the top plate 22, see Figure 6, and the arm is provided with a roller 103 riding upon the periphery of the crank disk 75. As previously stated, the forward end of the top plate 22 is recessed to a depth indicated at 42, this recess permitting the carriers to travel downwardly about the forward sprocket 38, and also providing for the upward movement of the portion 100 of the stop arm 98. When the lobe 76 of the cam 75 engages the roller 103, the arm 98 is moved upwardly, moving the upwardly extending end portion of the arm through the top plate 22 between the guide rails 43 and into the path of movement of the carrier blocks 40 as each block is advanced in juxtaposition to the cutter blades 54, 55.

The arrangement of the cam lobe 76 relative to the crank pin 78 is such that the stop arm 98 is elevated into carrier stopping position prior to the end of the indexing movement of the sprocket 38 and the carrier abuts against the face 101 just prior to the end of the movement of the carrier, whereby the compression spring 87 in the tubular member 80 is compressed and accordingly maintains the carrier against the stop member under a yielding pressure.

Provision is also made to accurately locate the carriers 40 in a direction transversely of the conveyor chain. A block 108 is secured to the top plate 22, as by screws 109. This block is formed with spaced apertures to receive guide pins carried by a shoe 110. The block is recessed intermediate the guide pins to receive a compression spring 111 urging the shoe inwardly toward the conveyor. A screw 112 serves as a stop for this inward movement of the shoe. The leading end of the shoe is chamfered, and is engaged by the outer side edge of each of the carrier blocks 40 as it is advanced in juxtaposition to the cutting knives, and the block is moved inwardly toward the knives with the outer depend-

ing flange 45 of the block engaging the outer face of the adjacent guide rail 43, see Figure 4. This arrangement accurately positions the appendage from the pivot pin 80 of the cutter carrying arms 56, 57. This arrangement avoids the necessity of initially constructing the machine with precision and effects accurately positioning of the appendage carriers regardless of wear of the parts incident to the operation of the machine.

The shaft 70 is also provided with a cam 115 which is effective to move the cutting blades to open position, as shown in Figure 3. An actuating arm 116 is pivotally mounted intermediate its ends to a bracket 117 depending from the under side of the top plate 22, see Figure 8. An adjustable link 118 is pivotally connected to one end of the arm and extends upwardly through an aperture in the top plate, and is connected to the lower cutter arm 57 by a pin 119.

An adjustable linkage 120 is connected to the arm 116 on the opposite side of its pivot 121, and this linkage also extends through the top plate and is connected to the upper cutter arm 56, as by cap screw 122. The rear end portion of the arm 116, to which the linkage 120 is connected, is urged downwardly by a helical compression spring 124 interposed between the arm and the top plate 22, see Figure 8. This portion 30 of the arm is also provided with a cam roller 125 riding upon the periphery of the cam 115, see Figures 4 and 8. The cam 115 is formed with a low portion which permits the spring 124 to depress the rear portion of the arm 116 and through the linkage 118, 120, the arms 56, 57, are moved toward each other by spring 124 to move the cutter blades 54, 55, Figure 4, into trimming engagement with the appendage 32. As will be understood, the cams 75, 115, are so relatively positioned on the shaft 70 that the cutter blades are moved by the spring 124 into trimming engagement with the appendage after the carrier 40 has been accurately positioned in register with the trimming blades, as previously explained.

The carriers 40 are advanced downwardly about the forward conveyor sprocket 38 in a two-step movement. In the initial step or portion of this movement, the carriers are moved from horizontal position to vertical position, as shown in Figure 2. During the subsequent portion of their advancement, the carriers are moved from the vertical position to the inverted position in proximity to the accumulating table 28. During these movements of the carriers, means is provided to retain the trimmed appendage in the carriers until the carriers have reached the inverted position with the appendage in close proximity to the accumulating table.

During the initial downward movement of the carriers about the sprocket 38, the appendages are retained in plates 46 by an arm 130 depending from a bracket 131 secured to the forward edge of the top plate 22. This arm 130 is formed of thin spring material and yieldingly engages the appendage with a slight pressure sufficient to retain the appendage in the recess 58 of the carrier, see Figure 2.

As previously explained, during the dwell of the conveyor, the ratchet arm 89 is being moved forwardly. This arm has secured to it on the pivot bolt 88 a second arm 134 extending forwardly and formed with an elongated slot 135. An arm 136 is journaled on the shaft 37 and 70 is provided with a stud 137 movable in the slot

135. Accordingly, during the dwell of the conveyor, the arm 136 is being rotated upwardly in a clockwise direction, Figure 6. A blade 138 is pivotally mounted on the outer end of the arm 136 and is urged toward an adjustable stop screw 139 by a torsion spring 140. When the arms 89, 134 have been moved forwardly their full stroke, the arm 136 assumes the position shown in Figure 10 with the blade 138 contacting the lower edge of the spring arm 130. At this time, the stud 137 is in the lower end of the slot 135 in the arm 134. Upon further rotation of the crank disk 75, the vertically positioned carrier is moved downwardly, and the arm 136 with the retaining blade 138 moves downwardly by gravity in unison with the movement of the carrier, the blade 138 yieldingly engaging the appendage and supporting it in the concavity 50 in the carrier. This downward movement of the arm 136 continues until it engages an adjustable stop screw 139 carried by a transversely extending support 140 at which time the crank pin 79 has reached center position, and the advancement of the carrier ceases. Also, at this time the appendage carried by the carrier is in close proximity to the accumulating table 28, see Figure 2. Upon forward movement of the connecting rod and arms 89, 134, the blade 138 will be moved upwardly while the conveyor is dwelling. When the blade 138 is moved upwardly out of engagement with the appendage, the same is deposited by gravity onto the table top. However, due to the close proximity of the appendage to the table top, the same is not damaged.

The apparatus is operated by a motor 142 mounted on the housing of a gear reduction 143 which, in turn, is supported by brackets 144 and braces 145 extending rearwardly from the forward legs 21. The output shaft of this power unit is provided with a pair of sprockets 146, 147. A driving chain 148 is trained over the sprocket 146 and a sprocket 149 journaled on the shaft 70. A chain 150 is trained over the sprocket 147 and over a sprocket 151 on the gear reduction 30 to effect rotation of the turn table 28 at slow speed. The bore of the sprocket 149, Figure 9, is formed on opposite sides with keyways 152. The shaft 70 is slotted, as at 153, to receive a flat key 154, the ends of which project into the keyways 152. A collar 155 is fixedly secured to the shaft 70 in proximity to the sprocket 149, the sprocket and the collar being arranged on the shaft intermediate the bearings 71 and by which the sprocket and collar are restrained against axial movement.

The outer end portion of the shaft 70 is bored to slidably receive a rod 158 slotted near its inner end to receive the key 154. A compression spring 161 is arranged in the bottom of the bore and yieldingly urges the rod and key to the left, Figure 9, so that the ends of the key move into the keyways 152 of the sprocket. The collar 155 is formed with similar keyways 162. Normally, the ends of the key 154 are positioned in the keyways in the sprocket by action of the spring 161. The outer end of the rod 158 is formed with a square portion 163, or otherwise formed to take a crank. If it is desired to operate the machine manually, as for example during the initial adjustment of the appendage carriers, or the plates 46, the crank may be applied to the end of the rod 158 and the rod pushed inwardly, moving the key 154 out of the keyways 152 and into the keyways 162 of the

collar 155, and the shaft 70 rotated manually by the crank.

The apparatus further includes means for positively dislodging the severed particle from the cutting blades 54, 55. This means consists of a leaf spring 165 secured to the under side of the upper cutter arm 56 adjacent the outer edge thereof, see Figure 4. The spring 165 terminates in proximity to the cutter blade 54 and is arranged to engage the severed particle 166 prior to the meeting of the cutting blades 54, 55, whereby at that time the spring blade 165 is under some tension and accordingly propels the severed piece 166 downwardly, passing through an opening 167 formed in the lower blade arm 57, and an opening 168 formed in the top plate 22 below the cutters.

In operation, the apparatus is arranged in proximity to the delivery of appendage moulds. 20 These moulds are opened, the appendages removed, and the flash or seam removed from the appendages by an operator known as a seamer. This operator places the appendages in the carrier plates 46. The trimmed appendages are deposited upon the accumulating surface 28 where a supply is available to the handler who applies the appendages to the ware. The apparatus is operated at a speed comparable to the seaming and sticking operations, with the 30 result that the appendages are properly and uniformly trimmed and made available to the handler without interruption or delay.

What I claim is:

1. Apparatus for automatically trimming appendages for pottery ware comprising a frame, a conveyor operable to intermittently advance an endless series of appendage carrying members to and past a trimming station, cutter means mounted at said station and being movable into trimming engagement with appendages carried by said carrying members, a stop member arranged in predetermined fixed relation to said trimming cutters and being cooperable with each carrier as the same is presented at said station to limit the advance movement of the carrier, and means operable to yieldingly hold said carriers against said stop members.

2. Apparatus for trimming appendages for pottery ware including a frame, a conveyor comprising an endless series of carriers, an appendage receiving block mounted in each carrier, said blocks being adjustable lengthwise and transversely of said conveyor, and means cooperable to secure said blocks in adjusted position, a trimming station arranged in juxtaposition to said conveyor, means operable to cause said conveyor to intermittently advance a procession of said carriers to and past said station, a pair of normally spaced apart cutters mounted at said station and being operable when moved into nipping engagement to trim an appendage positioned at said station, and means operable to accurately position said carriers transversely and lengthwise of said conveyor relative to said cutters as the carriers are successively presented at said station.

3. Apparatus for trimming appendages for pottery ware comprising a frame, an elongated track structure mounted on the frame, a conveyor operable to intermittently advance a series of appendage carrying members along said track, a trimming station arranged in juxtaposition to said track, a pair of trimming cutters mounted at said station and being movable into nipping engagement to trim appendages carried by said

carriers as the same are successively presented to said station, a stop member, means operable to actuate said stop member into engagement with each carrier as the same arrives at said station, means operable to yieldingly urge said carrier against said stop member and motion transmitting mechanism for operating said conveyor, stop member, and cutters, in timed relation.

4. Apparatus for trimming appendages for pottery ware comprising a frame, a conveyor having an upper and lower horizontal run and being operable to intermittently advance a series of appendage carrying members along said upper run to and past a trimming station, and downwardly to said lower run, and to effect inversion of said carriers during such downward movement, cutter means mounted at said station and operable to trim the appendage carried by each of said carriers as the same are successively presented at said station, means cooperable to retain said appendages in said carriers during said downward movement and inversion thereof, and being operable as each carrier approaches said horizontal run to release said appendages.

5. Apparatus for trimming appendages for pottery ware comprising a frame, a conveyor having an upper and lower horizontal run and being operable to intermittently advance a series of appendage carrying members along said upper run to and past a trimming station, and downwardly to said lower run, and to effect inversion of said carriers during such downward movement, cutter means mounted at said station and operable to trim the appendage carried by each of said carriers as the same are successively presented at said station, an accumulating conveyor for accumulating trimmed appendages arranged in proximity to the lower run of said conveyor, means operable to retain said appendages in said carriers during the downward movement and inversion thereof, and being operable as the carriers approach said horizontal run to effect deposit of the trimmed appendages on said accumulating conveyor.

6. Apparatus for trimming appendages for pottery ware comprising a frame, a conveyor having an upper and lower horizontal run and being operable to intermittently advance a series of appendage carrying members along said upper run to and past a trimming station and downwardly to said lower run, and to effect inversion of said carriers during such downward movement, cutter means mounted at said station and operable to trim the appendage carried by each of said carriers as the same are successively presented at said station, an appendage accumulating conveyor arranged in juxtaposition to the lower run of said first mentioned conveyor, means carried by the frame and cooperable to retain appendages in said conveyor during the initial downward movement thereof, and a second means cooperable to retain said appendages in said carriers during the remainder of said downward movement and being movable out of appendage retaining relation as each carrier is moved in proximity to said accumulating conveyor.

7. Apparatus for trimming appendages for pottery ware comprising a frame, a conveyor operable to intermittently advance an endless series of appendage carrying members to and past a trimming station, a pair of normally spaced apart trimming cutters mounted at said station and being simultaneously movable into trimming engagement with appendages carried by said carriers as the same are successively advanced to

said station, and means yieldingly engaging the portion of the appendage severed by said cutters during the trimming operation and, upon completion of said operation, discharging said severed portion from the cutters.

8. Apparatus for trimming appendages for pottery ware comprising cutter means operable to trim an appendage, an appendage holding fixture operable to support an appendage in juxtaposition to said trimming cutters, means operable to effect initial advancement of said fixture from trimming position through an arc about a horizontal axis, and thereafter complete such advancement to effect inversion of said fixture, a fixed member cooperable to hold the appendage in said fixture during such initial advancement, and a movable member cooperable to retain said appendage in the fixture during said subsequent advancement thereof.

20 9. Apparatus for trimming appendages of pottery ware comprising a pair of normally spaced apart cutters mounted for movement about a common axis into and out of nipping relation, a conveyor including an endless series of appendage carrying members, means operable to cause said conveyor to successively move said carriers in juxtaposition to said cutters and position the appendages supported by said carriers in position to be engaged by said cutters, a stop member ar-

25 ranged in predetermined relation to said cutters and being movable into engagement with each carrier as the same is moved into juxtaposition to the cutters, means yieldingly urging said carriers against said stop member, and actuating means operable while each carrier is so positioned in relation to said cutters to effect nipping engagement of the cutters.

10. Apparatus for automatically trimming appendages for pottery ware comprising a frame, a track extending along the frame, a trimming station arranged in juxtaposition to said track, a conveyor including an endless series of appendage carrying members arranged for sliding movement along said track, said conveyor being operable to intermittently advance said appendage carrying members along said track and present said carriers successively at said station, a pair of cutters arranged at said station and movable about a common axis into and out of nipping engagement, a stop member arranged in juxtaposition to said station and being movable into engagement with each carrier as the same is presented at said station and being operable when moved into engagement with a carrier to stop advancement thereof with the appendage supported by the carrier in position to be engaged by said cutters when the same are moved into nipping engagement, means yieldingly urging said carriers against said stop member, means mounted at said station and operable to yieldingly urge said carriers a predetermined distance transversely of said track, and motion transmitting mechanism operable to effect intermittent movement of said conveyor, cutter means and stop member in timed relation.

11. Apparatus for trimming appendages for pottery ware comprising a pair of normally spaced apart cutters, an appendage holding fixture operable to support an appendage with the terminal portion thereof in juxtaposition to said cutters, said cutters being movable in opposite directions into engagement with the terminal portion of the appendage supported by said fixture in nipping relation within the thickness of the appendage, and means operable to yield-

11

ingly clamp the appendage to the fixture during said nipping engagement.
